(57) **CLAIM**

The ornamental design for a fuel line assembly package, as shown and described.

DESCRIPTION

FIG. 1 is a rear elevation view of a fuel line assembly package showing my new design without the claimed portion of tubing for clarity of detail;

FIG. 2 is a front elevation view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is a perspective view thereof showing the claimed portion of tubing therewith.
